DESIGN FOR A DRESS

Yetta Levy, New York, N. Y.

Application September 27, 1935, Serial No. 58,736

Term of patent 3½ years

To all whom it may concern:

Be it known that I, Yetta Levy, a citizen of the United States of America, residing in Manhattan, county of New York, and State of New York, have invented a new, original, and ornamental Design for a Dress, of which the following is a specification, reference being had to the accompanying drawing, forming part thereof, wherein,

The tie and the horizontal bars extending out from the center panel in Fig. 1 are of mesh.

I claim:

The ornamental design for a dress, substantially as shown, and described.

YETTA LEVY.
